UNITED STATES PATENT OFFICE.

FREDERICK W. COLE, OF NEWTON, MASSACHUSETTS, ASSIGNOR TO THE GAMEWELL FIRE-ALARM TELEGRAPH COMPANY, OF NEW YORK, N. Y., A CORPORATION OF NEW YORK.

FIRE-ALARM-TELEGRAPH APPARATUS.

No. 923,114.

Specification of Letters Patent.

Patented May 25, 1909.

Application filed October 24, 1908. Serial No. 459,323.

To all whom it may concern:

Be it known that I, FREDERICK W. COLE, of Newton, county of Middlesex, State of Massachusetts, have invented an Improvement 5 in Fire-Alarm-Telegraph Apparatus, of which the following is a specification.

This invention relates to fire-alarm telegraph apparatus, and more particularly to a signal-box especially adapted for school-houses and other buildings or industrial plants where a drill-signal in addition to a fire-alarm signal is required.

The invention has for its object to provide a signal-box with circuit-operating devices for operating two independent electric-circuits and to provide an actuating-device adapted to operate both of said circuit-operating devices and also to provide an actuating device independent of the 15 aforesaid actuating-device for operating one of said circuit-operating devices independently of the other. Also to so arrange said actuating-devices that access may be had to one of them when the box door is closed and 20 to the other when the box door is open.

The invention also has for its object to provide a signal-box with means for transmitting what is herein termed a drill-signal consisting of a local signal-transmitter 30 adapted to operate a circuit containing one or more gongs or other signal-receiving instruments, which are arranged throughout a building or locality, and also to provide the signal-box with means for transmitting a fire-alarm signal, consisting of a circuit-operating switch adapted to operate an auxiliary circuit by which an auxiliarized fire-alarm box may be operated, and to provide 35 a single actuating-device for operating both the local signal-transmitter and the circuit-operating switch, so that by a single operation both the drill-signal and the fire-alarm signal will be transmitted, and to provide an independent actuating-device for 40 the local signal-transmitter whereby it may be operated independently.

The invention also has for its object to arrange the actuating-device which is employed to operate both the local signal-transmitter and the circuit-operating switch, on 45 or adjacent to the door, and in such manner that it is accessible at the outside thereof when the door is closed, so that it may be

operated without opening the door, and to arrange an independent actuating-device 55 for the local signal-transmitter within the box so that it can be operated independently of the circuit-operating switch when the box door is opened. The actuating-device for both the local signal-transmitter and for the 60 circuit-operating switch may be arranged on the box door back of or adjacent to an opening therethrough which is covered or otherwise protected by any suitable frangible 65 protecting-device. By breaking the frangible device on the door, both the auxiliarized fire-alarm box and the local alarm throughout the building or locality will be operated, as is required in case of fire, and upon opening the box door the local signal-transmitter may be operated independent 70 of the auxiliarized fire-alarm box and the local alarm only transmitted throughout the building or locality, as is required in case of a drill exercise. In both cases the same 75 alarm is given throughout the building or locality.

The invention also has for its object to provide for controlling the transmission of the signals incident to the operation of both 80 the auxiliary-circuit-switch and the local signal-transmitter by the closing of the box door, so that when said door is closed the only act which can be performed by the operator results in the transmission of both 85 signals.

The invention also has for its object certain improvements in the construction of the actuating-means for the local signal-transmitter; also in the actuating-means for the 90 circuit-operating switch for the auxiliary-circuit; and also in the construction of the winding-device for the local signal-transmitter.

Figure 1 is a front elevation of a signal-box embodying this invention, it being represented in connection with an auxiliary fire-alarm circuit and with a local alarm circuit, and having its door open to more fully illustrate the invention. Fig. 2 is a rear 100 view of the local signal-transmitter. Figs. 3, 4 and 5 are details to be referred to. Fig. 6 is a modification to be referred to. Figs. 7 and 8 show a different arrangement of the circuits.

e represents the signal-wheel of the local

signal-transmitter, which is contained in a case c having a door c' , and c' , c'' the contact pens which constitute an operating-device for a local alarm circuit b , which extends throughout a school-house or other building or locality, and as herein shown, contains a battery b' and any number of gongs b'' , or other signal-receiving instruments. The signal-wheel is rotated any number of rounds by a motor of any suitable construction. A motor, such as may be employed is here shown.

c represents the winding-shaft of the motor which is connected in any suitable manner, as by a ratchet and pawl, (not shown) with a toothed wheel c' , to the hub of which one end of the main spring c^2 is connected, the other end of said spring being connected to a fixed support c^3 . Said toothed wheel engages a pinion c^4 secured to a shaft c^5 bearing a toothed wheel c^6 , which engages a pinion c^7 secured to a shaft c^8 , bearing a toothed wheel c^9 , which engages a pinion c^{10} , secured to a shaft c^{12} , bearing an escape-wheel c^{13} .

The signal-wheel a is secured to the shaft c^5 . The motor is normally wound so that when let off the signal-wheel will be revolved three or more rounds to transmit the local alarm, and, as here shown, it is arranged to be manually rewound after each signal has been transmitted. To provide for thus arranging the motor a stop-pin c^{14} is arranged on one of the wheels of the train, as for instance, on the wheel c^6 , which, when the motor is wound engages the end of a locking-lever, herein shown as the arm c^{15} of a bell-crank lever, which is pivoted at c^{16} , the other arm c^{17} of said bell-crank lever extending over the free end of a releasing-lever, herein shown as a spring-arm c^{18} attached to the frame at c^{19} , see Fig. 3. The spring-arm has attached to it, near its outer or free end, a button c^{20} , see Fig. 4, the stud bearing said button extending through a hole in the main frame-plate d which supports the transmitter. Hence the button is accessible at the opposite side of said frame-plate. Pressure upon the button acts to depress the spring arm to disengage the bell-crank lever. A spring c^{22} engages the bell-crank lever and acts to move it on its pivot when permitted to act. Said spring normally holds the bell-crank lever with its arm c^{17} in engagement with the spring-arm c^{18} . When said spring-arm is moved by pressure upon the button and disengages the bell-crank lever the latter will be moved on its pivot by said spring c^{22} and the arm c^{15} moved to disengage the stop-pin c^{14} as shown in Fig. 3. The bell-crank lever is restored to its normal position to engage the stop-pin c^{14} by the operation of the winding-shaft as the train operates, and, as herein shown, said shaft has projecting from it a

pin c^{25} , see Fig. 2, in the plane of the bell-crank lever, which, when said shaft has been turned by the main spring a predetermined distance and the train has been operated to rotate the signal-wheel a predetermined number of rounds, will engage the arm c^{15} of the bell-crank lever and restore said lever, moving it into position to be engaged by the stop-pin c^{14} on the train. The button c^{20} is arranged on the front side of the frame-plate d , so that when the box door c' is open it is accessible. Therefore, upon opening the box door c' , the button may be pressed, and the releasing-lever operated to release the locking-lever, thereby permitting it to operate and release the local signal-transmitter, and the local alarm will be transmitted and the gongs or other signal-receiving instruments which are connected in the local signal circuit throughout the building, or other locality will be operated. The winding-shaft c also extends through the frame-plate d and its squared end is, therefore, accessible when the box door c' is open, so that it may be wound by a proper key or handle.

In case the box door has been opened and the local or drill alarm operated it is very important that the local signal-transmitter shall be rewound before the box door is closed, in order that it may at all times be set ready to be operated, after the box door is closed, by other actuating means provided for the purpose, as will be hereinafter described. To make sure that the local signal-transmitter has been thus rewound a plate f is provided, see Fig. 5, which is adapted to occupy two different positions, one when the local transmitter is wound and the other when it is unwound, and the box door has projecting from its inner side a pin g , which is so disposed with relation to said plate as to engage said plate when the transmitter is unwound and thereby prevent the closing of the door, but which will not engage said plate in case the transmitter is wound, to thereby permit closing of the door.

The position of the plate is controlled by the winding-shaft, and, as here shown, said plate is mounted loosely on the winding-shaft, and has an arm f^1 extending laterally from it provided with a projection f^2 which is arranged to be engaged by an arm f^3 secured to the winding-shaft, when said shaft is wound, to thereby move the plate out of the path of the pin g . As the winding-shaft is unwound the arm f^3 disengages the projection f^2 , and the plate is thereby permitted to move into the path of the pin g , and is moved by means of a spring f^4 attached to it. Movement of the plate is limited by a projection f^5 thereon moving in a hole f^6 in the frame-plate. Thus, when the box door is open and the local or drill signal transmitted, the door cannot be again closed until after the local signal-trans-

mitter has been rewound. The arm f^2 is also employed as a pointer to indicate whether or not the signal-transmitter is wound, and an indicating plate f^4 is provided, having thereon the word "Set", and said plate is so disposed with respect to the pointer that the pointer will point directly toward it when the transmitter is wound, and will point in an entirely different direction when the transmitter is unwound. Therefore, even though the plate f is omitted and likewise the pin g on the box door, the arm f^2 may still be employed as a visual indicator to show whether or not the transmitter is wound.

On the front side of the frame-plate d a circuit-operating device or switch for an auxiliary-circuit h is located. The auxiliary-circuit extends to an auxiliarized fire-alarm box of any suitable construction and containing an auxiliary-magnet h' , which is employed to let off or otherwise operate said fire-alarm box and the return-signal circuit-operating-device or switch h^2 . The auxiliary-circuit h is independent of the local alarm circuit b . The auxiliary-circuit operating-device, as herein shown, consists of a switch composed of a movable switch-arm and stationary switch-plates. The switch-arm is represented at i and is arranged on a pivot-stud and held in its normal elevated position by a spring i' surrounding said pivot-stud and connected to the arm. The switch-arm bears contact-pens which successively engage stationary switch-plates, three being herein shown, as i^4 , i^5 , i^6 , arranged about the axis of the switch-arm.

The auxiliary-circuit wires h , h , lead respectively to the frame bearing the switch-arm and to the plate i^4 , and as the switch-arm normally bears on said plate i^4 the auxiliary-circuit is normally closed. The battery h^5 in said auxiliary-circuit is very light, so that notwithstanding the circuit is closed the armature of the auxiliary-magnet h' in the fire-alarm box is retracted. A circuit-wire j leads from the plate i^5 to the auxiliary-circuit h , at one side of the battery h^5 , and said circuit-wire includes a heavy open circuit battery j' . A circuit-wire j^2 also leads from said plate i^5 to a buzzer-magnet k . A circuit-wire j^3 leads from said buzzer-magnet to the plate i^6 . As the switch-arm passes from the plate i^4 to the plate i^5 , the normally closed auxiliary circuit is broken, but when said plate i^5 is engaged a new circuit is established as the circuit-wire j will be then included in the auxiliary-circuit, together with its heavy battery j' , in series with the battery h^5 in the auxiliary-circuit, and as a result there will be then a strong current on the auxiliary-circuit, resulting in the operation of the auxiliary magnet in the fire-alarm box. As the switch-arm

passes from the plate i^5 the buzzer-magnet is also included in the circuit and its armature will be immediately attracted ready to respond upon action of the return-signal switch in said box, which switch is so arranged as to be opened by the operation of the signaling train of the fire-alarm box immediately after it has started. Opening the auxiliary-circuit will cause the armature of the buzzer-magnet to retract, it being carried back by the action of a flat spring on which it is mounted on the frame to which is also connected one end of the auxiliary-circuit. When in a normal state of rest the armature of the buzzer-magnet is held in an intermediate position between the pole of its magnet and a flexible contact spring k' , which is fastened to the plate i^6 , but when the armature flies backward after being released by the magnet its inertia will carry it far enough to make connection to the said contact spring k' . This connection will then include the buzzer-magnet in a closed loop circuit including the heavy battery which may be traced from spring k' through plate i^6 , wire k to the junction between the two batteries, then through battery j' , wire j , plate i^5 , wire j^2 , magnet k , wire j^3 , plate i^6 , switch arm i which is then resting on said plate i^6 and to the frame on which the switch is mounted, thence through the supporting spring to the armature. The magnet will thereupon be immediately energized to again attract its armature and said armature will thereafter buzz between the contact spring and poles of the magnet. This will continue while the switch-arm is held in engagement with the plate i^6 , and will constitute a return-signal to show that the box has been properly started to send its fire-signal to the fire-department to which it is connected. Said switch-arm i has a rearward and downward projection i^2 , see Fig. 4, which is located above and projects into the plane of the actuating-device e^{20} of the local signal-transmitter, so that when said switch-arm is depressed said projection i^2 will engage and press inward said actuating-device to thereby release the local signal-transmitter. Thus the local signal-transmitter may be operated by a downward movement of the auxiliary-circuit switch-arm in addition to being operated independently thereof by pressing inward the actuating-device e^{20} manually. This is for the purpose of enabling the local-signal to be transmitted simultaneously with the fire-alarm signal in case of a fire, and also for permitting a drill-signal to be transmitted independently of the fire-signal. Said switch-arm i also has a forward projection i^4 , see Fig. 4, which is adapted to be engaged by a pivoted actuating-lever i^3 , herein shown as mounted on the inside of the door e . The actuating-lever is ar-

ranged on the door in such manner that when the door is closed it will occupy a position above the projection i^3 of the switch-arm and when pulled down will engage and 5 depress said switch-arm to thereby operate the auxiliary-circuit. The actuating-lever i^3 is arranged back of an opening through the door so that access to it may be obtained without opening said door, and said opening 10 is covered or protected by a frangible protecting-device of any suitable construction having a glass plate o as a coöperative part of it. Upon breaking the glass plate o the actuating-lever i^3 may be engaged and 15 operated to thereby operate the auxiliary-circuit and also release the local signal-transmitter, and both the fire-alarm and the local-alarm or drill-signal will be transmitted, and upon opening the door and 20 pressing the button c^{20} the local-alarm or drill-signal only will be transmitted. As the actuating-lever i^3 is mounted on the door it will be observed that when said door is 25 open it will be removed from position to engage the auxiliary-circuit switch-arm. Thus it will be seen that when the box door is closed the only act which can be performed by the operator results in transmitting both the fire-alarm signal and the 30 drill-signal, the closing of the door controlling such operation.

In lieu of employing a normally wound local signal-transmitter I may employ a normally unwound local signal-transmitter 35 having a winding-lever n , see Fig. 6, which is adapted to be operated manually to wind the transmitter and to cause it to transmit its signal. Both wound and unwound signal-transmitters are well-known. Said winding-lever is arranged to be engaged by the auxiliary-circuit switch-arm i when the latter is operated. With this modification of 40 my invention the local signal-transmitter can be operated with the fire alarm signal and also independently thereof.

Instead of arranging the local signal-transmitter and the auxiliary circuit switch-arm in independent circuits they may be otherwise arranged. Referring to Fig. 7, 50 the heavy battery circuit j is extended by wire j^{11} from the switch-plate w , to one side of the local signal-transmitter T , and then by wire j^{12} from the other side of said transmitter to the heavy battery j' , being connected with said battery at an intermediate point, so as to include a portion thereof, and 55 said circuit wire j^{12} includes the bell b^2 or other signal receiving instrument. By referring to Fig. 8 the electro-magnet of the bell b^2 may be made as a higher resistance magnet and the circuit wire j^{12} may extend to a point beyond the heavy battery j' to thereby include the whole of said battery in 60 the local electric circuit and not destroy its efficiency for fire-alarm purposes as the cir-

cuit-operating device for the local signal-transmitter would not be between the switch and the heavy battery, and hence would not prevent the switch from operating the auxiliary circuit. By this arrangement both 70 batteries and branches of the auxiliary system would be under continual test. These modifications illustrate different ways of arranging the circuits, and is intended to show that the invention is not limited to 75 any particular arrangement of the circuits.

Having thus described my invention, what I claim as new and desire to secure by Letters Patent is:—

1. In a fire-alarm telegraph apparatus, 80 the combination of two electric-circuits, a circuit-operating device for each circuit, an actuating-device for actuating both circuit-operating devices, and an actuating-device independent of the aforesaid actuating-device for actuating one of said circuits independently of the other, substantially as described.

2. In a fire-alarm telegraph apparatus, 85 the combination of two electric-circuits, a signal-box into which said circuits lead, comprising a case having a door, a circuit-operating-device for each circuit contained in said case, an actuating-device for actuating both circuit-operating devices, accessible 95 when the door is closed, and an actuating-device, independent of the aforesaid actuating-device, for actuating one of said circuit-operating-devices only, accessible when the door is open, substantially as described.

3. In a fire-alarm telegraph box, the combination of an auxiliarized signal-box and an auxiliary-circuit connected therewith, of a case into which said auxiliary-circuit 105 leads, a local signal-transmitter contained in said case adapted to operate an independent electric-circuit, means contained in the case for operating both the auxiliary-circuit and the local signal-transmitter and means for 110 operating the local signal-transmitter independently of the auxiliary circuit, substantially as described.

4. In a fire-alarm telegraph apparatus, 115 the combination with an auxiliarized signal-box and an auxiliary-circuit connected therewith, of a signal-box comprising a case into which said auxiliary-circuit leads, and having a door, a local signal-transmitter contained in said case, adapted to operate a local alarm circuit, means for operating said auxiliary-circuit and said local signal-transmitter, when the door is closed, and means for actuating the local signal-transmitter 120 independently when the door is open, substantially as described.

5. In a fire-alarm telegraph apparatus, 125 the combination with an auxiliarized signal-box and an auxiliary-circuit connected therewith, of a signal-box comprising a case into 130

which said auxiliary-circuit leads, and having a door, means contained in said case and controlled by said door for operating said auxiliary-circuit, a local signal-transmitter 5 also contained in said case adapted to operate a local alarm circuit, and actuating means therefor adapted to be operated by the auxiliary-circuit actuating-means when the door is closed, and accessible when the door is open to be operated independently thereof, substantially as described.

6. In a fire-alarm telegraph apparatus, the combination with an auxiliarized signal-box, an auxiliary circuit connected therewith, of a signal-box comprising a case, into which said auxiliary-circuit leads, and having a door, a switch for said auxiliary-circuit contained in said case, an actuating-device for said switch arranged on the door 15 which is movable by the door into and out of position to engage said switch, a local signal-transmitter also contained in said case, adapted to operate an independent electric-circuit, and an actuating-device 20 therefor, independent of said switch, but arranged to be operated by the movable member thereof, substantially as described.

7. In a fire-alarm telegraph apparatus, a combination of two electric-circuits, a signal-box having a door, and having a switch for operating one of said circuits and also having a box-number signal-transmitter for operating the other circuit, and two actuators, one for operating said transmitter and 35 the other for operating both said switch and transmitter, of which the latter only is accessible when the box door is closed and of which the former is accessible only when the box door is open, substantially as described.

40 8. In a signal-box having a door, and having two circuit-operating-devices for operating two independent circuits, and two actuators, one adapted when operated to operate one of said circuit-operating-devices and 45 transmit a signal, and the other adapted when operated to operate both circuit-operating devices and transmit both signals, the transmission of a signal incident to the operation of one circuit-operating device only 50 being prevented by the closing of the box door, substantially as described.

9. In a fire-alarm telegraph apparatus, the combination with an auxiliary-circuit, for an auxiliarized signal-box, and a local alarm-circuit, of a signal-box comprising a case into which both said circuits lead, and having a door, a local signal-transmitter contained in said case for said local alarm-circuit, means for operating said local signal-transmitter, and means for operating both 55 said auxiliary-circuit and said local alarm-circuit, the operation of said local signal-transmitter only being prevented by the closing of the box door, substantially as described.

10. In a signal-box, a case, an auxiliary-circuit switch in said case, an actuating-device for said switch, combined with a local signal-transmitter also in said case, an actuating-device therefor, independent of said switch but arranged to be engaged and operated by the movable member thereof, substantially as described.

11. In a signal-box, a case having a door, a local signal-transmitter in said case, an actuating-device therefor, accessible when said door is open, combined with an auxiliary-circuit switch in said case, the movable member of which is arranged to engage and operate said actuating-device, an actuating-device for said movable switch member arranged on the door and accessible at the outside thereof, and a frangible protecting device for said actuating-device, substantially as described.

12. In a signal-box, a case, an auxiliary circuit switch in said case comprising stationary switch-plates and a movable switch-arm, an actuating-device for said switch-arm, combined with a local signal-transmitter also in said case, and an actuating-device therefor arranged in the path of movement of said switch-arm, substantially as described.

13. In a signal-box, a case having a door, an auxiliary-circuit switch in said case comprising stationary switch-plates and a movable switch-arm connected with the auxiliary circuit, an actuating-lever for said switch-arm, arranged on the door and accessible at the outside thereof, combined with a local signal-transmitter also in said case, and an actuating-device therefor, which is disposed in the path of movement of said switch-arm, and which is accessible when the door is open to be independently operated, substantially as described.

14. In a signal-box, a case, an auxiliary-circuit switch in said case comprising stationary switch-plates and a movable switch-arm, an actuating-device for said switch-arm, combined with a local signal-transmitter also in said case, a locking-lever therefor, a releasing-arm for said locking-lever, and a button on said arm located in the path of movement of said switch-arm, substantially as described.

15. In a signal-box, a case, an auxiliary-circuit switch in said case comprising stationary switch-plates and a movable switch-arm having a forwardly and downwardly extended projection, and an actuating-lever engaging said projection, combined with a local signal-transmitter also in said case, and an actuating-device therefor arranged in the path of movement of said projection, substantially as described.

16. In a signal-box, a case having a door, an auxiliary-circuit switch in said case comprising stationary switch-plates and a mov-

able switch-arm, a pivoted actuating-lever on the door arranged to engage said switch-arm and a frangible protecting plate for said actuating-lever, substantially as described.

17. In a signal-box, a signaling-train having a stop-pin on one of its wheels, a locking-lever engaged by said stop-pin, a spring for moving said lever to disengage the stop-pin, a spring-acting releasing arm for releasing said locking-lever, permitting said spring to act, having a button by which it may be depressed, substantially as described.

18. In a signal-box, a signaling-train having a stop-pin on one of its wheels, a locking-lever engaging said stop-pin, a spring for moving said lever to disengage the stop-pin, a releasing-arm for releasing said locking-lever, permitting said spring to act, and means operated by the winding-shaft of the signaling-train, when the train operates, to

restore said locking-lever to its locking-position, substantially as described.

19. In a signal-box, a case having a door, a pin on the inside of the door, a signaling-train contained in said case adapted to be normally wound, a plate, and means connected with the winding-shaft for moving said plate out of position to be engaged by the pin on the door, and independent means for moving said plate into position to be engaged by the pin on the door when it is disengaged by the means connected with the winding-shaft, substantially as described.

In testimony whereof, I have signed my name to this specification, in the presence of two subscribing witnesses.

FREDERICK W. COLE.
